UNITED STATES PATENT OFFICE.

THOMAS MACKELLAR, OF PHILADELPHIA, PENNSYLVANIA, ASSIGNOR TO
THE MACKELLAR, SMITHS & JORDAN COMPANY, OF SAME PLACE.

DESIGN FOR TYPE.

SPECIFICATION forming part of Design No. 16,739, dated June 15, 1886.

Application filed April 29, 1886. Serial No. 200,029. Term of patent 14 years.

To all whom it may concern:

Be it known that I, THOMAS MACKELLAR, (assignor to the MACKELLAR, SMITHS & JORDAN COMPANY,) of the city and county of Philadelphia, Pennsylvania, have invented and produced a new and original Design for a Font of Printing-Type, of which the following is a specification.

The nature of my design is clearly shown in the accompanying typographic impression, to which reference is made; and it consists of an unshaded letter the distinguishing feature of which is the inclined line at the top of the letter, as in the A, B, H, I, K, M, N, P, R, S, T, and X, and upon the right hand at the bottom of the letter, as shown in the C, G, H, I, K, L, M, N, R, U, X, and Y. The C, G, E, and S are ornamented by the inclined line crossing the face, as shown.

Having now described my invention, I claim as new—

The design for a font of printing-type, as shown, the same consisting of an unshaded letter the distinguishing feature of which is the inclined line at the top of the letter, as in the A, B, H, I, K, M, N, P, R, S, T, and X, and upon the right-hand at the bottom of the letter, as shown in the C, G, H, I, K, L, M, N, R, U, X, and Y, and the C, G, E, and S ornamented by the inclined line crossing the face, as shown.

THOS. MACKELLAR.

In presence of—

C. F. HUCH,
HERMAN METIUS.
